CLAIM

The ornamental design for a set of utensils, as shown and described.

DESCRIPTION

FIG. 1 is a perspective view of a set of utensils, showing our new design.

FIG. 2 is a top view thereof;

FIG. 3 is a bottom view thereof;

FIG. 4 is a right-side view thereof;

FIG. 5 is a left-side view thereof;

FIG. 6 is a rear view thereof, shown in enlarged scale; and, FIG. 7 is a front view thereof, shown in enlarged scale.

The broken lines in the drawings are for showing portions of the set of utensils only and form no part of the claimed design.

1 Claim, 7 Drawing Sheets
